CLAIM

The ornamental design for a flashlight, as shown and described.

DESCRIPTION

FIG. 1 is a perspective view of a flashlight showing my new design;

FIG. 2 is front elevational view of the flashlight;

FIG. 3 is a top view thereof;

FIG. 4 is a bottom view thereof;

FIG. 5 is a left-side elevational view thereof;

FIG. 6 is rear view thereof; and,

FIG. 7 is a right-side elevational view thereof, the knurled bands being illustrated only partially in FIGS. 2–7 whereas the knurling actually extends all the way around the flashlight as indicated in FIG. 1.
